UNITED STATES PATENT OFFICE

2,599,865

STOP MECHANISM FOR SLIDING ELEMENTS
OF FURNITURE

Edward G. Rudman, Nashua, N. H.

Application April 13, 1950, Serial No. 155,725

3 Claims. (Cl. 211—1.3)

1

This invention relates to a slide stop for the sliding element or elements of furniture.

Many articles of furniture such as desks, tables, and cabinets of various types, are provided with sliding elements which may consist of extension leaves or rests, and/or drawers or bins; and frequently the construction is such that the sliding element may be extended from either of the opposite sides of the article of furniture of which it forms a part.

The object of the present invention is to provide a stop for limiting the extension of the sliding element in either direction.

A further object of the invention is to provide a stop as mentioned which will not stick or bind, work loose, or otherwise get out of order irrespective of atmospheric conditions.

A further object of the invention is to provide a device of the class mentioned which cannot accidentally lock the sliding element either in extended or retracted position.

Other objects of the invention are to provide a device as mentioned which shall be quiet in operation, and which needs no adjustment or care after initial installation.

Other objects will appear hereinafter.

With the above objects in view, the invention consists generally in an article of furniture, a sliding element therein adapted to be extended from opposite sides of said article of furniture, said element having a groove in the under face thereof extending parallel to the direction of movement of said element, and terminating at each end in a stop shoulder, a dog pivoted below and adjacent said sliding element and having a free end adapted to be moved into said groove in the path of said stop shoulder, and means actuated by the movement of said sliding elements to move said dog into operative position.

The invention further consists in various details of construction and arrangements of parts, all as will be fully described hereinafter and particularly pointed out in the claims.

The invention will be more readily understood by reference to the accompanying drawings forming a part of this specification, and in which:

Fig. 1 is a vertical longitudinal section of a table equipped with a sliding extension element adapted to be extended from opposite sides of the table, and illustrating, in full lines, the element extended from one side of the table, and in dotted lines as extended from the opposite side thereof, the section being taken on the line 1—1 of Fig. 2;

2

Fig. 2 is a bottom plan view of the device as illustrated in Fig. 1;

Fig. 3 is a detail transverse section on the line 3—3 of Figs. 1 and 2; and

Fig. 4 is a detail view of the grooved face of the sliding element.

Referring to the drawings, 10 indicates the top of a table, 11 and 12 the opposite sides of the body of the table, and 13 the legs thereof. 10 The upper edges of the sides 11 and 12 are recessed as at 14 to receive a sliding extension element 15; said element being provided with a groove 16 in its under face and extending longitudinally of the slide, that is in the direction of movement thereof. The groove 16 terminates short of the ends 17 or 18 of the slide forming abutment shoulders 19 and 20, respectively.

Pivotedly mounted, as on transverse pins 21, adjacent the grooved face of the slide 15, and 20 adjacent the sides 11 and 12 of the table are similar stop dogs 22 and 23 respectively. The dogs 22 and 23 extend inwardly from the pivot pins 21 and are adapted to be swung upwardly to project the ends thereof into the groove 16 and into the path of the shoulders 19 and 20.

Rigidly connected to the dogs 22 and 23 are actuating arms 24 and 25, respectively, which are laterally offset therefrom and adapted to engage the adjacent under face of the slide. 30 The dogs 24 and 25 are angularly fixed to the dogs 22 and 23, so that when the ends of the arms are in engagement with the face of the slide, the dogs will be projected into the groove 16.

35 In the construction illustrated in the drawings, the dogs and their respective actuating arms are mounted between strips 26 extending between the sides 12 of the table, and preferably close under the slide; the pins 21 having their bearings in said strips.

The operation of the device is as follows. When the sliding element is retracted, that is, within the body of the table or other article of furniture with which the device is used, the 45 ends of the arms 24 and 25 engage the adjacent face of the slide 15 and thereby hold the ends of the dogs 22 and 23 within the slot 16. Should the slide 15 be extended to the left as illustrated in full lines in the drawings, the stop shoulder 20 will engage the end of the dog 22 thereby stopping further extension of the slide 15. Should the slide be retracted and then extended from the opposite side of the table, the shoulder 19 will engage the dog 22 and depress the same 55 below the face of the slide, at the same time

raising the end of the arm 24 above the level of said under face. This is possible in that the end of the slide with the abutment 19 will have passed inwardly beyond the arm 24. During the movement of the slide to the right, as above stated, the end of the slide adjacent the shoulder 20 will engage the arm 25, depressing the same to the position shown in dotted lines in Fig. 1, and raising the end of the dog 23 into the groove 16 in position to be engaged by the shoulder 19.

It is obvious that a stop mechanism as above described will be silent in operation, will not stick or bind, and will not lock the sliding element in either extended or retracted position. It is also obvious that after installation no further adjustment or care is necessary.

While the invention has been described and illustrated as applied to a table having an extension slide, it is obvious that the same is applicable to desks, cabinets or other objects of furniture and that the sliding element may, if desired, be a drawer or storage compartment. Also, the article of furniture to which the invention is applied may be either portable or a permanent fixture.

It is to be understood that various details of construction and arrangements of parts may be made without departing from the scope of the invention as described and within the scope of the appended claims.

I claim:

- An article of furniture including a body portion and a sliding element adapted to be extended from said body portion, said sliding element having a groove in the under face thereof and extending longitudinally in the direction of movement of said element, said groove terminating short of the end of said sliding element forming a stop shoulder, a dog pivotally mounted beneath said groove and an arm rigidly connected to said dog and having an end engageable with said slide laterally of said groove to move said dog with said groove in the path of said shoulder.
- An article of furniture including a body portion and a sliding element adapted to be optionally extended from opposite sides of said body

portion, said sliding element having a groove in the under face thereof and extending longitudinally in the direction of movement of said element, said groove terminating adjacent the ends of said sliding element forming a pair of stop shoulders, a dog pivotally mounted beneath said groove at the opposite ends thereof and normally extending upwardly and inwardly into said groove, and an arm rigidly connected to each of said dogs and extending upwardly and outwardly into engagement with the under face of said sliding element laterally of said groove.

3. An article of furniture including a body portion and a sliding element adapted to be optionally extended from opposite sides of said body, said sliding element having a groove in the under face thereof and extending longitudinally in the direction of movement of said element, said groove terminating adjacent the ends of said sliding element forming stop shoulders, a pair of laterally spaced strips rigidly mounted beneath said sliding element, a dog and an actuating arm for said dog pivotally mounted between said strips adjacent each end thereof, each of said dogs extending inwardly and upwardly beneath said groove and said arms extending upwardly and outwardly to engage with the under face of said slide laterally of said groove.

EDWARD G. RUDMAN.
